UNITED STATES PATENT OFFICE.

GEORGE E. HARRISON AND GEORGE BURNS, OF DETROIT, MICHIGAN

GUARD FOR THE ARMS OF ELECTRIC-CONDUCTOR SUPPORTS.

No. 914,042.

Specification of Letters Patent.

Patented March 2, 1909.

Application filed May 25, 1908. Serial No. 434,840.

To all whom it may concern:

Be it known that we, GEORGE E. HARRISON and GEORGE BURNS, citizens of the United States, residing at Detroit, county of Wayne, State of Michigan, have invented a certain new and useful Improvement in Guards for the Arms of Electric-Conductor Supports, and declare the following to be a full, clear, and exact description of the same, such as will enable others skilled in the art to which it pertains to make and use the same, reference being had to the accompanying drawings, which form a part of this specification.

15 This invention relates to sheaths for the arms of electric conductor supports.

It has for its object an improved sheath adapted to be used over an arm, or a part of an arm, on which the lineman may stand, or 20 which he may otherwise contact while engaged in stretching wires or repairing the electric wires stretched over said arms, and which will protect the lineman from the electric shock incident to such position.

25 Where lines carrying currents of high tension are stretched over the ordinary glass or porcelain supports, which are mounted on pins, and the pins driven into the arms, there is great liability to more or less severe shocks 30 from induced currents, or from the electricity that leaks from the wires, although the lineman may not come in direct contact with the wire itself. The danger is especially pronounced in damp weather, or after rains, 35 when the arm has become coated with a film of moisture, and is especially liable to happen when, as is not infrequently the case, the arm has been affected by decay, which may be only in spots, and may be partially covered 40 by paint, and of a character to escape the observation of the workman, but is sufficiently advanced to cause the partially decayed wood to hold moisture, and thereby become a conductor of electricity to a sufficient degree to be troublesome, and sometimes dangerous.

The object of this invention is to cover that part of the arm over which, or around which, the workman is employed, with a 45 sheathing of rubber, or other similar non-conducting material, which is itself dry and which may be easily placed and easily removed after use, but which affords a perfect and adequate protection to the workman 55 from the dangerous or troublesome effects referred to.

In the drawings:—Figure 1, is a perspective of a sheath. Fig. 2, is a cross section of a sheath in place on an arm. Fig. 3, indicates the manner of using the sheath.

60 The sheath is an open ended split tube adapted to engage closely over the arm, and to that end is nearly rectangular in cross section. The tread part 2 is provided with notches 10 and 11 at the ends, which are 65 adapted to engage closely against the pins 8 and 9 of the insulators proper. From the tread 2 depend hanging walls 3 and 4, which are made to converge or draw in slightly, making the cross distance between the lower 70 edges of the hanging walls 3 and 4 slightly less than the cross distance of the upper edges of these walls. At the bottom of each hanging wall is an inturned flange, and the two flanges 5 and 6 engage under the lower 75 face of the cross arm 7, when the guard is in position for use. The material, of which the guard is made, is somewhat flexible and resilient, and the bottom edges of the hanging walls 3 and 4 can be sprung apart to permit 80 of the engagement of the guard over the arm 7; the tread part 2 can be flexed enough to bring the notches 10 and 11 into their proper engagement with the pins 8 and 9. With a guard made of reasonably stiff material, the 85 construction described will suffice to cause the guard to hold its position firmly enough for practical use. Provision is made, however, by attaching a strap 12 to one of the flanges 5, and a buckle 13 to the flange 6 to 90 firmly secure the guard in place, if, for any reason, it fails to fit the particular arm with which it is desired to use it. The arms, or electric supports of this character, are at the present time made of a standard size, or 95 two standard sizes, and the arms are spaced on the pole at a standard distance, and the pins spaced a standard distance, and therefore it is possible to make the guard of a standard size, or two standard sizes, to cor- 100 respond.

In use the workman generally stands on one arm of the support and hooks his leg over the next higher arm; this brings the bottom of one foot onto an arm, and the 105 lower part of the thigh and the back of the calf against the next higher arm; the shields are adapted to protect him in this position.

What we claim is:—

1. A guard for electric linemen's use, comprising a tread part of insulating material provided with notches at its ends, hanging

members connected with said tread part and provided with inturned flanges, substantially as described.

2. A guard for linemen's use, comprising a tread part, and side members hanging therefrom, and means for securing the guard to an arm, substantially as described.

In testimony whereof, we sign this specification in the presence of two witnesses.

GEORGE E. HARRISON.
GEORGE BURNS.
